UNITED STATES PATENT OFFICE.

ALFRED WILLIAM SOUTHEY, OF EDGWARE, LONDON, ENGLAND.

METHOD OF PRODUCING GASEOUS FUEL.

1,083,468.

Specification of Letters Patent.

Patented Jan. 6, 1914.

Application filed November 12, 1912. Serial No. 730,969.

To all whom it may concern:

Be it known that I, ALFRED WILLIAM SOUTHEY, a subject of the King of Great Britain and Ireland, residing at Cherry 5 House, Hale Lane, Edgware, London, England, have invented new and useful Improvements in and Relating to the Methods of Producing Gaseous Fuel, of which the following is a specification.

10 This invention relates to the production of gaseous fuel from liquid hydrocarbons for motive power purposes in apparatus wherein the fuel is ignited in a chamber to which air is freely admitted at approximately atmospheric pressure.

According to the present invention I prevent excessive combustion by supplying the liquid fuel to the chamber in the form of a spray of finely atomized oil, by means of 20 which a large excess of oil or vapor is assured, so that when combustion occurs, it occurs in the presence of a substantial excess of oil, which has the effect of keeping the metal surfaces in the generator comparatively cool. The combustion is further effected by a highly concentrated flame so as to obtain as high a temperature and as large a degree of fixation as possible, while at the same time the damping effect of the 25 excess of oil prevents an over combustion of the gas, thereby producing an excess of burnt gas. In addition, the amount of air drawn into the apparatus is regulated by the suction of the engine alone, and the 30 liquid fuel being always largely in excess, and in a finely atomized state, there is continuously formed the amount of fixed gas or gaseous fuel required by the engine. The excess of liquid fuel may be collected in the 35 bottom of the chamber, whence it can be drawn off by the pump or other means which produces the spray. As the combustion is to be regulated by the amount of air drawn in by the suction of the engine I prefer to 40 atomize the liquid fuel by means of a mechanical spraying nozzle and thereby avoid using an air or steam blast, as the use of either of these would interfere with the proper regulation of combustion within the 45 chamber.

The present invention accordingly consists in a novel method for preventing excessive combustion by supplying the liquid fuel in the form of a spray in sufficient quantity to insure the combustion taking place 50 in the presence of a substantial excess of oil.

The invention further consists in a method for regulating the supply of air by the suction of the engine to form the combustible mixture with the atomized or vaporized 60 fuel, in which mixture the atomized fuel is substantially in excess.

The invention further consists in supplying the liquid fuel in the form of a spray produced mechanically by a nozzle, as distinguished from a spray produced by an air or steam blast.

The accompanying drawings, by way of example, show in Figure 1, a diagrammatic view of a gaseous fuel generator for an internal combustion engine with fuel supply and circulating pump, according to this invention, and in Figs. 2 and 3 respectively, a sectional side elevation and plan of a generator on these lines.

In Fig. 1, *a* represents the trough of the producer connected by the passage *b* to a float chamber *c* which is in turn connected to an oil reservoir *d*. Connected to the passage *b* is a duct *e* leading to a circulating 80 pump *f* driven by the engine, which pump is connected by a pipe *g* to a spray nozzle *h* in the upper portion of the producer. A short passage *i* connects the float chamber to the duct *e*. The upper portion of the 85 generator comprises a domed cover *j* having one or more air inlets *k* in its lower edge. Within this cover is a concentrically disposed bell *l* into the upper portion of which the spray nozzle *h* opens. The lower peripheries of the cover *j* and the bell *l* are but a little distance apart leaving only a small annular passage into the generator 90 trough for air introduced by the inlets *k*. Concentrically within the bell is a coned 95 baffle *m* the outer edge of which is lower than the edge of the bell *l*, the peripheries of the bell and the baffle forming between them an annular opening for the spray or vapor produced within the bell to pass, 100 which opening is below the first annular opening referred to. The lower edge of the baffle is some short distance above the liquid level maintained in the trough by the float. Within the baffle the gas outlet *n* projects 105 above the level of the fuel in the trough.

Referring to the details of the apparatus shown in Fig. 2, the baffle *m* may conveniently be carried upon arms *o* from the base of the outlet pipe *n*. For starting, a pilot 110 flame is obtained from a wick *p*, which is carried in a box *q* on the side of the pro-

ducer, and is fed with oil from the trough *a*. The flame is drawn in through the hole *r* when the engine is started. The nozzle *h* is one of known construction, having two channels such as *t*, oppositely directed, for producing two fine jets of oil which impinge on the surrounding sleeve and are atomized. I have found it of advantage for facilitating the smooth operation of the pump which circulates the liquid, and for preventing it from knocking, to admit a minute quantity of air into the duct *e*, by means of a small pipe *u* having at the top a hole about $\frac{1}{16}$ " in diameter and extending downward below the opening *v* where the oil can flow from the float feed *c* to the duct *e*. This air has no material effect upon the spray. The pump may be a diaphragm pump worked from the tappet of the engine.

20 The operation of the apparatus is as follows: On the engine being started, the pump commences to deliver oil through the spraying nozzle *h*, and air is drawn in through the inlets *k*. The wick *p* (Fig. 2) is lighted and the flame drawn in through the opening *r*. This ignites the atomized fuel with which the chamber is filled, and combustion and fixation proceed, the air entering through the ports *k* to the extent required and regulated by the suction of the engine and mixing with the excess of atomized fuel from the nozzle *h*. The flame of combustion is mainly concentrated around the lower edge of the baffle *m* and the fixed gas and products of combustion pass away to the engine by the outlet *n*. The free supply of oil through the nozzle *h* keeps the baffle *m* and the interior of the chambers *j* and *l* comparatively cool. The oil as consumed is 40 made up by the float feed from the tank *d*.

What I claim as my invention is:—

1. The method of producing gaseous fuel for internal combustion engines from liquid fuel consisting in supplying liquid fuel

without air in the form of a spray to a 45 chamber where it is partly burnt with air introduced thereinto at atmospheric pressure and normal temperature independently of the fuel, the liquid fuel being supplied in such quantities that partial combustion 50 always takes place in the presence of a substantial excess of fuel.

2. The method of producing gaseous fuel for internal combustion engines from liquid fuel, consisting in supplying the liquid fuel 55 without air and in excess in the form of a spray produced mechanically to a chamber where a portion of said liquid fuel is partially burned with air introduced into said chamber at normal temperature independently 60 of the fuel.

3. The method of producing gaseous fuel for internal combustion engines which consists in introducing liquid fuel into a chamber in excess of the requirements and in the 65 form of a number of fine streams, drawing air at normal pressure and temperature by suction into said chamber independently of the fuel, and partially burning a portion of said fuel in the presence of said excess of 70 fuel.

4. The method of producing gaseous fuel for internal combustion engines from liquid fuel which consists in introducing liquid fuel into a chamber in excess of the requirements and in the form of a number of fine streams, drawing air at normal pressure and temperature by suction into said chamber independently of the fuel where it mixes 75 with a portion of said fuel, partially burning a portion of said mixture in the presence of said excess of fuel and returning the excess of fuel to the source of supply. 80

ALFRED WILLIAM SOUTHEY.
